The ornamental design for a cushioning material for packaging, as shown and described.

DESCRIPTION

FIG. 1 is a front view of a cushioning material for packaging showing our new design;

FIG. 2 is a rear view thereof;

FIG. 3 is a bottom view thereof; a top plan view being symmetrical to the bottom view thereof;

FIG. 4 is a right side view thereof, a left side view being symmetrical to the right side view thereof;

FIG. 5 is a cross-sectional view thereof along the line 5-5 in FIG. 1;

FIG. 6 is a cross-sectional view thereof along the line 6-6 in FIG. 1;

FIG. 7 is a partial enlarged view thereof, showing detail 7 in FIG. 1;

FIG. 8 is a partial enlarged perspective view of detail 8 in FIG. 7;

FIG. 9 is a partial enlarged view of detail 9 in FIG. 3;

FIG. 10 is a partial enlarged view of detail 10 in FIG. 5; and, FIG. 11 is a partial enlarged view of detail 11 in FIG. 6.

The dot-dot-dash broken lines indicate cross-sections or enlarged areas.

The dot-dash broken lines define the bounds of the claim.

The dashed broken lines depict portions of the cushioning material for packaging.

The broken lines form no part of the claimed design.
